UNITED STATES PATENT OFFICE.

HARLEY MELVIN WRIGHT, OF DARLINGTON, OKLAHOMA.

TELEPHONE SYSTEM.

1,131,455.

Specification of Letters Patent.

Patented Mar. 9, 1915.

Application filed March 12, 1914. Serial No. 824,124.

To all whom it may concern:

Be it known that I, HARLEY MELVIN WRIGHT, a citizen of the United States, and a resident of Darlington, in the county of Canadian and State of Oklahoma, have made certain new and useful Improvements in Telephone Systems, of which the following is a specification.

My invention relates to party line telephone systems in which the central station is provided with a selective switch for calling subscribers and for locking out such subscribers as are not called.

Reference is made to the accompanying drawings forming a part of this specification, and in which like letters indicate like parts.

Figure 1 is a diagram showing a central station, and the nearest one of the subscribers' stations, this being a part of a lockout system in which the subscribers' stations are not provided with hand controlled selective switches. Fig. 2 is a diagram constituting a continuation of the lockout system just mentioned in connection with Fig. 1, and showing a number of subscribers' stations, certain parts being omitted for the sake of clearness. Fig. 3 shows fragmentarily, a line provided with the lock out system just mentioned, and illustrated the comparative condition of the stations locked out and thus connected. Fig. 4 is a plan view of my improved electrically operated switch as constructed for general use in various forms of my system.

Fig. 5 is a section on the line 8—8 of Fig. 4 looking in the direction of the arrow. Fig. 6 is a section on the line 9—9 of Fig. 4 looking in the direction of the arrow. Fig. 7 is a detail showing one of the movable armatures forming a part of the mechanism shown in Fig. 4. Fig. 8 is a detail showing an armature forming a part of the mechanism appearing in Fig. 6. Fig. 9 is an elevation showing a telephone box as used in connection with one form of my system. Fig. 10 is similar to Fig. 11, but showing the telephone box as open. Fig. 11 is a view partly in elevation and partly diagrammatic showing my improved hand operated switch employed at the central station. Fig. 12 is a section on the line 16—16 of Fig. 11, looking in the direction of the arrow. Fig. 13 is a section on the line 19—19 of Fig. 12 looking in the direction of the arrow. Fig. 14 is a detail being

a section on the line 18—18 of Fig. 12 and showing one of the contact members carried upon the switch arm in said figure. Fig. 15 is an elevation of the hand operated switch used at the central station and appearing in Fig. 11.

In Fig. 1 the line wires are shown at 21, 22, and at the central station these line wires are connected with short wires 23, 24. The wire 23 leads to a line drop 25, and in series with this drop is a wire 24, leading to a contact 24^a. This line drop is of the ordinary construction commonly known in this art. A movable spring 24^b constitutes one member of this contact, which normally remains closed, as may be understood from Fig. 1. Two conducting cords 26, 27, are respectively secured to contact members 26^a, 27^a, forming a jack connection. A wire 26^b is connected with the contact 26^a and also with the wires 21 and 23. The conducting cords 26 and 27 are also connected with contact members 28, 29, forming a part of a ringing key at the central station. This ringing key is provided further with contact members 30, 31, 32, 33. Wires 34, 35, are connected with the contact members 31, 32, and are also connected with wires 36, 37. The line drop 25 is disconnected only when the central operator inserts either the calling plug or the answering plug into the jack. Whenever the cords 26 and 27 are connected with the jack, the line wire 22 is connected with the conductor 27 and the contact 24^b disconnects the contact 24^a, while the cord 26 is connected to the line wire 21. The wire 36 is connected by a wire 38 with a winding 41 forming a part of an ordinary clearing out drop 40 located at the central station. The winding 41 has such impedance and resistance as to make it most effective, and still prevent the talking currents (the frequency of which is comparatively high) from passing through it; the winding 41 is connected by a wire 42 with the wire 37. A listening key of the central station is shown at 44, and connected with this listening key are two wires 45, 46, which lead to the operator's set. Connected with the contact member 30 is a wire 47.

A wire 48 is connected with the wire 47 and leads to a hand controlled switch 49 located at the central station, and shown more particularly in Fig. 15. Connected with the contact member 33 is a wire 50 which is

connected with a wire 51 leading to the switch 49. A wire 52 is connected with the wires 50, 51, and with a push button 53, the latter being normally open. Another wire 54 is connected with the wires 47, 48, and with a contact 55 which is normally open. A wire 56 is connected with this contact and with another wire 57, the latter being connected to a generator 58. This generator is adapted for producing both alternating and direct pulsating current. The contacts 53 and 55, together constitute a double-contact push button for controlling the alternating current as supplied to the line. 10 A wire 59 is connected with the wires 56, 57, and communicates, through the medium of the hand switch 49, with the generator 58. The switch 49 is always connected to the alternating or direct circuit of the generator, but does not energize the line until the switch arm is moved angularly for the purpose, so as to close a particular set of contacts as elsewhere described. A wire 63 is connected with the ground 64 and with the switch 49. The electrically operated switch is shown at 65. This switch is shown diagrammatically in Fig. 1, and is hereinafter more particularly described as to its mechanical structure, with reference to Figs. 15 4 to 8 inclusive.

The subscriber's magneto is shown at 66 and the subscriber's local battery at 67. A wire 68 connects this battery with the transmitter 69, and from the latter a wire 70 leads to a contact member 71, this and another contact member 72 being the so-called "talking" contact members. From the contact member 72 a wire 73 leads to the primary winding 74 of the induction coil, and from this winding a wire 76 leads to the local battery 67.

The primary winding 74 is in inductive relation to a secondary winding 75. The subscriber's switch hook is shown at 77 and the receiver, normally hanging thereon, at 78. Connected with the switch hook 77 is a wire 79. A wire 80 leads from the receiver 78 to a condenser 81, and connected with the latter is a wire 81^a. A short wire 83 connects the wire 81^a with the line wire 21, and with a wire 84. Connected with this wire is a wire 82 which leads to the electrically operated switch 65. A wire 85 is connected with the wires 82, 84, and leads to the magneto 66. A wire 86 is connected with this magneto and with a short wire 87, the latter being connected with the line wire 22. A wire 88 is connected with the wires 86, and 87, and with the electrically operated switch 65. Wires 89, 90, are connected with this switch in a manner hereinafter described. Connected with the wire 90 are two wires 91, 92, and connected with the wire 89 are two wires 93, 94. The manner in which the wires 91, 92, 93, 94, and various other wires

are connected with the switch 65 is set forth below.

A wire 95 is connected with the secondary winding 75 and with a contact spring 127. A wire 97 is connected with the receiver 78 70 and with a contact spring 128, these two contact springs being mounted upon the electrically operated switch 65, and more particularly described below in connection with the mechanical description of said 75 switch. A wire 99 is connected at each of its ends to said switch, as described below. A wire 100 is connected with the switch and with the ground.

The mechanical construction of the electrically operated switch is shown in Figs. 7 to 11 inclusive. There are six windings 101, 102, 103, 104, 105 and 106. The two windings 104, 105, are mounted concentrically upon a single core 107 which is made of soft 85 Norway iron, adapted to polarize easily by magnetic induction. Another core 108, similarly constructed and also readily magnetized, carries a single winding 106. A core 109 similar to the core 108 carries the 90 single winding 101, and a core 110 similar to the core 107 carries the two windings 102, 103 disposed concentrically. The various parts are supported upon a base 111.

Four yokes 112, 113, 114, 115, are provided for facilitating the completion of the magnetic circuits through the respective cores. The yokes 113, 114, are made of soft Norway iron thoroughly annealed. The yokes 112 and 115 are made of tungsten steel 100 permanently magnetized, and having their south-seeking poles extending upwardly and thus by magnetic induction rendering the cores 107, 110, magnetic, the north-seeking poles of these cores extending upward. The yokes are supported upon plates 116, 117 of non-magnetic material secured to the base 111. Two frames 118, 119, made of non-magnetic material are mounted upon the supporting plates 116, 117. Journaled in the frame 118 is a shaft 120, and a shaft 121 is journaled partly in the frame 118 and partly in the frame 119. Mounted rigidly upon the shaft 120 is a polarized armature 122, and mounted upon this armature is a 115 finger 123 made of non-magnetic material, preferably brass.

Secured upon one end of the finger 123 is an armature 124 having the form of a disk and made of annealed iron so as to be unpolarized. The armature 124 extends through an opening 125 made for the purpose in the yoke 113. Mounted upon the supporting plate 116 is a bracket 126. Supported by this bracket are two contact springs 127, 128, the spring 128 being uppermost. Above the contact spring 128 is a projecting tongue 129, constituting another contact spring. The contact springs 127, 128, are insulated from each other, and 130

from adjacent metallic parts by blocks 130 of insulating material. The contact spring 128 carries, at its inner or free end, a stirrup 131 secured rigidly upon it and thus 5 movable with it.

A small metallic disk 132 is carried by the contact spring 128 and projects slightly to the right beyond the end of said spring, as indicated in Fig. 5. This disk is made of 10 annealed iron, and by becoming magnetized under action of the magnetic yoke 112, serves to hold the contact spring 128 in firm engagement with the contact spring 127 whenever the armature 122 is attracted 15 from its normal position. Each time the armature 122 is attracted as just stated the disk 132 is raised relatively to the core 108. The disk 132 and the stirrup 131 are insulated from the contact spring 128. The 20 purpose of the stirrup 131 is to trip the disk 132 against the finger 123 whenever the stirrup 131 is actuated as hereinafter described, so as to disconnect the contact member 128 from the contact member 127. Secured 25 upon the underside of the armature 122 is a leaf spring 133 made of German silver, this spring at its free end resting upon the core 107.

Mounted upon the shaft 121 is a polarized 30 armature 134, and secured upon the underside of this armature is a leaf spring 135, the free end of which rests upon the core 110. This leaf spring is made of German silver, and tends to hold the armature 134 in normal position; that is, in such position 35 that the armature 137 rests against the core 109. Similarly, the spring 133, which is of German silver, tends to hold the armature in normal position,—so that the armature 124 40 rests upon the core 108.

A finger 136 made of non-magnetic material such as brass is carried by the armature 134. A disk shaped armature 137 is carried by the finger 136 and extends 45 through an opening 138 in the yoke 114. The shaft 121 carries a crank arm 139 which extends through the yoke 131. The two fingers 123, and 136 are held in position by screws 140, 141, extending directly through 50 them. The fingers are bowed slightly at the points where the screws extend through them. By turning the screws the fingers are flexed so as to shift the positions of the armatures 122, 134, slightly in relation to the 55 respective cores with which these armatures are associated. The screws 140, 141, are thus used to adjust the sensitiveness of the armatures 122, 134. The armature 122 carries a clapper 142 mounted rigidly upon it 60 and extending downwardly into proximity to a gong 143, so arranged that when the armature 122 is attracted by the core 107, the gong is struck by the clapper and thus sounded. The armature 134 carries a clapper 65 per 144 secured rigidly to it and extending

downwardly in close proximity to a small gong 145 so positioned as to be struck by the clapper 144 as the latter is swung from its normal position as the armature 134 is actuated. See Fig. 6. The armatures 122 70 134 are formed as indicated in Figs. 7 and 8, the armature 122 being provided with a wedge shaped groove 122^a, and the armature 134 being similarly provided with a wedge shaped groove 134^a. These grooves are 75 merely for the purpose of facilitating the connection of the fingers 122, 136, with the respective armatures, and are not in all instances essential.

Mounted upon the base 111 are a number 80 of binding posts 147 and connected with the latter are a number of wires 147^a, the latter being adapted for connecting them with and disconnecting them from the various windings, in order that the windings may be arranged differently at the respective subscribers' stations. To facilitate this purpose I also provide short wires 147^b, which extend merely from one binding post 147 to another. By aid of the wires 147^a, 147^b, I 90 can readily disconnect the windings from the binding posts and connect them up again in a different order. The purpose of this arrangement may be more readily understood by reference to Figs. 1 and 2. In Fig. 95 1 I show the windings as connected with various wires in the most convenient manner to adapt the subscriber's switch for a particular one of the stations; or in other words, as subscriber's station No. 1. In this instance the winding 103 is connected with the wires 82 and 89; the winding 102 is connected with the wires 90 and 88; the winding 101 is connected with the wires 99 and 100; the windings 105 and 106 are connected 100 with the wire 99; the winding 106 being also connected with the wire 94; the winding 104 is connected with the wires 91, 93. As a result of the connections just described, the windings 104, 105, and 106 are essentially 110 arranged as a delta, the corners of the delta being connected respectively with the windings 101, 102 and 103.

The connections of the various windings 115 relative to each other at subscribers' stations numbered 2 to 10 inclusive are shown in Fig. 2. The connections of the windings 101, 102, 103, are never changed relatively to the line wires 21, 22 and the ground wires 100, and are consequently alike at each of the 120 respective subscriber's stations. The interconnections, as between the windings 104, 105 and 106, however, are at the various stations made as shown in this figure. It will be understood, however, that the relative 125 positions of the various windings are not changed, as the windings are not moved relatively to each other, the virtual positions of the windings 104, 105, 106 being altered by suitably connecting the ends of these 130

windings relatively to each other. For instance, at subscriber's station number 1, windings 104 and 105 are virtually transposed as compared with these parts connected at subscriber's station number 2. In altering the connections for the windings in question, their polarity as compared with the permanent polarity of the respective cores associated with them is in some instances changed, as indicated by the shifting of the legends N and S, as shown in Fig. 2.

At the subscribers' stations numbered 7, 8, 9 and 10, the windings 104, 105, and 106 are arranged to form star connections instead of delta connections. Where there are only six subscribers' stations the windings in question can readily be delta connected, but where the number of subscribers' stations is in excess of six, the additional stations thus added, that is, those numbered in excess of six, are best provided with star connections for the reason that the number of delta connections possible is limited. The same windings and other mechanical parts are used at all of the stations. When the star connections are employed, the windings should be made of larger size or some other provision should be made for equalizing and apportioning the relative resistances offered by the several subscribers' stations.

My purpose in forming the windings 104, 105, 106 into various star and delta permutations as just described is to render the subscribers' stations selective and to enable the lock-out mechanism of one subscriber's station to be operated while that of another station is left idle. When two subscribers' stations are in communication with each other, through the agency of the central station, as hereinafter described, these two stations must be free to communicate with each other and all other subscribers' stations on the line must be locked. For this purpose, and also for controlling the connecting and disconnecting mechanism of the respective subscribers' stations, and for the further purpose of enabling each subscriber to call any other subscriber without disturbing the central station, the relative arrangement of the winding as above described is essential. The manner in which these results are accomplished is set forth below.

I will now describe the mechanism of the switch 49 used at the central station for the purpose of controlling the party lines. This switch 49 is provided with a movable switch arm 148 carrying two contact plates 149, 150, which are insulated from the switch arm and from each other by a plate 148^a of insulating material. The contact plate 149 is provided with two contact tongues 149^a, and the contact plate 150 is provided with three contact tongues 150^a. I therefore conveniently refer to the contact plate 149 as a double contact plate and to the plate 150 as

a triple contact plate. The switch 49 is provided with a number of contact members of arcuate form distributed in a substantially semicircular row and designated as 151 to 166 inclusive. Concentric to this row of contact members is another row of contact members designated as 167 to 182 inclusive. Concentric to this row is another row of contact members 183 to 198 inclusive. A fourth row contains a number of contact members interspersed with pegs of insulating material, these parts being designated as follows: peg 199, contact members 200, 201; peg 202, contact members 203, 204, 205, 206; pegs 207, 208, contact members 209, 210; peg 211, contact member 212; peg 213, and contact member 214. Another row contains contact members from 215 to 229 inclusive and a single peg 230 of insulating material. As the switch arm 148 is moved angularly around, the double contact plate 149 and the triple contact plate 150 are brought into registry with various radially disposed groups of the contact members above designated. For instance, when the switch arm 148 is moved angularly upward according to Fig. 1, the contact members 151, and 167 are connected together by the double contact plate 149, and the contact members 183 and 215 are brought into communication through the medium of the triple contact plate 150.

The outer or sector shaped contact members 151 to 166 inclusive, because of their greater length measured in the arc of a circle, are engaged slightly prior to the engagement of other contact members disposed in a row radiating from the center of rotation of the switch arm. For instance, if according to Fig. 15 the switch arm 148 be swung upwardly over the contact members 215, 183, 167, and 151, the double contact plate 149 first engages the contact member 151 and then engages 167, and the triple contact member 150 brings the contact members 183, and 215 into metallic communication at the same instant that the double contact member 149 engages the contact member 167. The various pegs of insulating material shown in Fig. 19, such as those numbered 199, 202 and 207, have no electrical function and are merely employed to insure uniformity of contact pressure. In other words, they are inserted merely to fill intervals between the stationary contact metallic members.

The wire 60 engages the following stationary contact members: 182, 197, 196, 179, 178, 177, 176, 191, 190, 189, 172, 171, 170, 169, 168 and 167. The wire 61 is connected with the following contact members: 198, 181, 180, 195, 194, 193, 192, 175, 174, 173 and 188. The ground wire 63 is connected with the following contact members: 215, 216, 217, 218, 155, 156, 157, 222, 223, 224, 225, 226, 227, 228 and 229. The wire 59 is connected

with the following contact members: 183, 184, 185, 186, 187. The wire 48 is connected with the following contact members: 200, 153, 154, 219, 220, 221, 158, 159, 160, 161, 210, 212, 214. The wire 51 is connected with the following contact members 151, 152, 201, 203, 204, 205, 206, 209, 162, 163, 164, 165 and 166.

The various stationary contact members shown in Fig. 15 are arranged in radially disposed groups, each group representing a subscriber's station. The subscriber's station No. 6 is represented by five contact members 156, 172, 188, 204, and 220, as indicated by an appropriate legend on Fig. 15. The various other subscribers' stations numbered 2 to 11 are similarly represented by groups of contact members as indicated by appropriate legends in Fig. 15.

The legends just mentioned, and the respective rows of contact members associated therewith and referring to the separate subscriber's stations, are used in calling the station connecting them with the line and locking out other stations not called. The contacts of station No. 11 when used in connection with a lockout system may be used for ringing the lockout bells before connecting certain subscriber's stations with the line—thus insuring secret service by locking off all subscribers before connecting the line with the stations of the party or parties desiring to talk secretly. Other legends, however, such as numbers 1 and 2, numbers 3 and 4, numbers 5 and 6, numbers 7 and 8, groups of contact members associated with them and referring to the different subscribers' stations, are used only in connection with the act of restoring the line to normal condition after each secret conversation thereon between two subscribers, and in thus restoring the line to normal position, to ring a bell at each subscriber's station in order to apprise the subscribers that the line is no longer busy.

The groups of contacts designated in Fig. 15 as numbers 1 and 2, numbers 3 and 4, numbers 5 and 6, numbers 7 and 8, numbers 9 and 10, are employed in connection with alternating currents, which are rendered available by simply swinging the switch arm 148 to its fifth position, or in other words, from its normal position to the contact member 155. The push button contacts 53 and 55 and the switch 49 are never used simultaneously, as they are employed independently of each other. The purpose of the push button contacts 53 and 55 is to supply alternating current to the line in order to ring the lockout bells; also, when used with party lines or with individual lines, to ring alternating current bells.

With the form of my system shown in Figs. 1 and 2, when a subscriber wishes to talk to another and desires the conversation

to be secret, he actuates his magneto. The central answers and asks his number. The subscriber replies, giving his number and also the number of the station he desires called. The operator then presses the push button, so as to close contacts 53 and 55. This locks all of the subscribers' stations off of the line. She next releases the push button, swings the switch arm 148 to the number indicating the calling subscriber's station, and then pressing upon the switch arm, she energizes the line and this rings up the calling subscriber. She next swings the switch arm 148 to the number indicating the station of the subscriber called for, and then pressing upon the arm she calls the party in question. He answers, and the two parties desiring to converse secretly can do so. The effect of these movements is to connect both the station of the calling subscriber and the station of the subscriber called, and to lock out all other stations. The conversation being finished, the central operator swings the switch arm 148 back into its normal position and in so doing presses the switch arm, so as to cause it to close the contacts which it controls. As it passes successively over the last five positions indicated at the right of Fig. 15, the various subscribers' stations are all successively brought into normal condition. The subscribers' stations are then connected to the line by each connecting bell being rung with one short ring, the respective subscribers being thus apprised that the line is no longer busy.

The windings 104, 105 and 106, at the different stations, are connected differently in relation to the line, as indicated at Figs. 1 and 2. These figures show how the various windings 104, 105 and 106, at the respective stations, are virtually shifted in relative positions, each grouping or shifting of these windings having opposite polarity connections for the windings 104 and 105, as indicated by the legends N and S indicated in Fig. 2. The opposing polarities are obtained by transposing the terminals of the respective windings, so as to render them different at the respective stations. The winding 106 is not thus transposed, as it is not polarized. Therefore, it responds to current passing through it in either direction, and it locks the disk-like armature in its operating. The locking of the disk-like armature in its normal position prevents movement of the polarized armature, so that the windings 104 and 105 are unable to actuate it. The only time, therefore, the bell can operate is when no current is flowing through the winding 106, while the windings 104 and 105 are energized by current flowing through them in such direction as to strengthen the induced magnetism in the core carrying the windings 104 and 105. The connections for the windings 101, 102

and 103, controlling the lockout or disconnecting bells, are alike at all stations.

In Figs. 9 and 10 I show a convenient form of telephone box suitable for holding the various fixtures of the subscribers' stations as above described. The box or casing is shown at 389, the lid of the box appearing at 390. A number of metallic hinges are shown at 391 and may be employed to facilitate the connections. The lock is shown at 392 and is used for securing the lid in order to prevent unauthorized persons from opening the box. The electrically operated switch is mounted in the upper portion of the box as shown more particularly in Fig. 13.

I will now describe the operation of my system. If any subscriber lifts his receiver from the hook he will hear a click if the line is not busy. When this is the case the subscriber has free access to the line at all times. In case of such emergency that it is necessary to make a call even when the line is busy, this may be done by ringing the central station and using the code number of the subscriber calling. This notifies the central operator that the subscriber having the code number in question is ringing and that the case is one of emergency. The code numbers may conveniently be arranged as follows:—subscriber's station No. 1, one short ring and one long ring; station No. 2, two short rings; station number 3, three short rings, etc., the idea being that each station has some distinctive ring of its own. Whenever a subscriber uses a single short ring, that indicates that conversation is completed. When a subscriber's station is connected with a line and he desires to ring up the central station, this may conveniently be done with a single long ring. The disconnecting bell apprises the subscribers that the line is going to be busy. When the connecting bell of a subscriber gives one long ring it notifies him that he is wanted at the phone. When the central operator rings each connecting bell with one short ring it notifies all of the subscribers that a secret conversation has ended and that all of the subscribers now have access to the line.

The manner in which a secret conversation may be carried on is as follows:—Suppose that the subscriber at station number 2 wishes to talk secretly and that the line is in normal condition. The calling subscriber at station number 2 actuates his generator 66. This energizes the line and throws the line drop 25 at the central station. The central operator is thus notified that some person on the line wishes to make a call. The central operator thereupon closes her listening key 44 and requests the calling subscriber to state his number. The calling subscriber gives his own number, and states the number of the subscriber he desires to

call. The central operator then closes the ringing key, thus bringing the contact member 28 into engagement with the contact member 30, and also bringing the contact member 29 into engagement with the contact member 33. The central operator next closes the contacts 53 and 55. Generator 58, wire 62, contact 53, wires 52 and 50, contact members 33 and 29, conductor 27, contact 27^A, line wire 22, windings 102, 103, line wire 21, conductor 26^B, contact 26^A conductor 26, contacts 28 and 30, wire 47, contact 55, wires 56 and 57, back to generator 58. This throws the alternating current of the dynamo into the line wires 21 and 22 and energizes the windings 102 and 103. The current thus acting upon these windings causes the armature 134 to be attracted against the core 110. The small bell 145 is thus energized, and the crank arm 139 strikes the top of the stirrup 131. This in turn raises the iron rivet 132 from the magnet 112 and by so doing breaks the magnetic circuit affecting the rivet 132. This rivet being raised with the stirrup 131, raises the contact spring 128 out of engagement with the contact spring 127 and thus disconnects all of the subscribers' stations. The central operator next releases the push button controlling the two contacts 53 and 55 and at practically the same instant turns the switch arm 148, as shown in Fig. 15, to the set of contents containing the number of the calling station. The switch arm is pressed upon the contacts representing this station, thus sending the proper combination pulsating current over the line, to energize the connecting bell at this particular station. See Fig. 5. The current in question now energizes the windings 104 and 105, but not the winding 106. The armature 122 is thus caused to be actuated. This causes the bell 143 to sound and also swings the connecting finger 123 down against the adjacent insulated iron rivet 132. This rivet thereupon clings magnetically to the magnet 112, and by so doing holds the contact spring 128 against the contact member 127, the station under consideration being thus connected to the line. The central operator next places the switch arm 148 over the contacts representing the number of the station to be called. This I will suppose is at station No. 1. She next presses the switch arm upon the contacts last mentioned. This throws a pulsating current into the line, thus energizing the connecting bell at subscriber's station No. 1, by supplying a suitable selective ringing current thereto, and moving the armature 122 against the core 107. This causes the bell 143 to sound, and connects the contact member 128 to the contact member 127 by means of the finger 123 striking the iron rivet 132. This closes the talking circuit. The subscriber at station No. 2 can now talk secretly to the sub-

scriber he has called. The central operator next releases the listening and ringing keys, thus connecting the lines with the clearing out drop 40 so that when the secret conversation is finished either of the subscribers engaging in it can signal the central station by means of the line drop last mentioned. As above explained, one short ring made by the generator at a subscriber's station notifies the central operator that the secret conversation is finished. Upon learning this the central operator actuates her ringing key, closing contact members 29 and 33, and also 28 and 30. The central operator next presses the switch arm 148 while swinging the same and passing this arm over the first five sets of contacts at the right. The effect of this movement is to connect all of the subscribers to the line, the connections being made two at a time by the alternating current,—that is, one short ring, which apprises each subscriber that the line is no longer busy and that each subscriber's station is now connected to the line. The contact members 127, 128 are now closed and the line is in normal condition ready for use by any subscriber.

I do not limit myself to the precise construction shown, as variations may be made without departing from the spirit of my invention, the scope of which is commensurate with my claims.

I claim:—

1. In a party line telephone system having a central station and a number of subscribers' stations, the combination of an electrically operated switch located at each subscriber's station, said switch being provided with a polarized core, a plurality of windings mounted upon said core and disposed concentrically, a polarized armature mounted adjacent said core and controllable thereby, a contact located adjacent said polarized armature and adapted to be closed by a movement thereof, an adjacent armature polarized and located in such position that when drawn toward the polarized core it disconnects said contact, mechanism controllable from the central station for electrically energizing the core and polarized armature associated therewith at different subscribers' stations having different polarities in order to render them selective, mechanism controllable by a number of said electrically operated switches for connecting the subscriber's set with the line and locking out other subscribers' stations, and mechanism controllable by said electrically operated switches for disconnecting the subscriber's set and then connecting the stations of other subscribers desiring to engage in secret conversation.

2. In a party line telephone system provided with a central station and a plurality of subscribers' stations, the combination of

a plurality of electrically operated switches located at different subscribers' stations respectively, each switch being provided with polarized cores and armatures, the polarity of which at one station is different from that at another station in order to render them selective, mechanism controllable by said electrically operated switches for connecting the subscriber's set with the line and locking out other subscribers' stations, and mechanism controllable by said electrically operated switches for disconnecting the subscriber's set and then connecting the stations of subscribers desiring to engage in secret conversation.

3. In a telephone system having a central station and a plurality of subscribers' stations, the combination of a plurality of electrically operated switches located one at each station and provided with polarized magnets, the polarity of a magnet at one station differing from the polarity of a corresponding magnet at another station in order to render said electrically operated switches selective, means controllable from the central station for energizing said switches in order to render them selective, mechanism controllable from the central station for locking out such sets as are not connected with the line, connecting mechanism controllable by said switches for bringing the sets into communication with the line when said sets are not locked out, and means controllable by the central station for restoring the line to normal condition.

4. An electrically operated switch for subscribers' stations comprising a polarized core, a plurality of windings mounted thereon, and disposed concentrically, a polarized armature movable relatively to said core and controllable thereby, a contact located adjacent to said polarized armature and adapted to be closed by a movement thereof, and an adjacent armature polarized and located in such position that when it is actuated from normal position and drawn toward the polarized core, it disconnects said contacts.

5. An electrically operated switch comprising a contact, a stirrup mounted thereupon, an arm engaging said stirrup and adapted to move the same for the purpose of opening said contact, an armature connected with said arm and mounted to rock for the purpose of actuating said arm, a polarized magnetic member located adjacent to said armature for the purpose of energizing the same, and magnetic mechanism independent of said polarized magnetic member for actuating said armature.

6. An electrically operated switch for party lines comprising a contact, an arm in operative relation to said contact for the purpose of opening the same, a movable armature carrying said arm, said armature

being polarized, a polarized magnetic member disposed adjacent to said armature and having a plurality of windings adapted, when energized with right polarity, to actuate said armature; if non-polarity armature, connecting opposite shaft and to finger mounted upon said armature, is not energized by winding about said non-polarized magnetic member disposed adjacent to and 5 against said non-polarized armature, when in normal condition, a second polarized armature operating independently of said last-mentioned armature mechanism and located adjacent said contact member, a finger 10 mounted to be actuated by said second-mentioned polarized armature and in operative relation to said contact for the purpose of connecting the same, a polarized magnetic armature disposed adjacent to said second-mentioned polarized armature and having a plurality of windings adapted to be connected in different ways and connecting 15 said contacts when energized with right polarity to actuate said second-mentioned polarized armature if said second-mentioned non-polarized armature connected opposite said shaft and to said finger mounted upon said second-mentioned polarized armature is not energized by windings about 20

25 said non-polarized magnetic member disposed adjacent to and against said non-polarized armature, when in normal position.

7. A switch for party line telephone systems comprising a pair of contact members, one of which is provided with a stirrup for 30 moving it out of engagement with the other, an arm extending through said stirrup, an armature carrying said arm and mounted to rock in order to actuate said stirrup, a magnetic member disposed adjacent to said armature, a second armature located adjacent to said contact members, a finger mounted upon said second mentioned armature and extending into engagement with one of 35 said contact members for the purpose of actuating and connecting same, and a magnetic member disposed adjacent the said last mentioned armature for the purpose of energizing the latter, said magnetic member being polarized and provided with a plurality of independent windings.

40 In testimony whereof I have signed my name to this specification in the presence of two subscribing witnesses.

HARLEY MELVIN WRIGHT.
